ELECTRIC STORAGE BATTERY

Robert C. Slatterback, Toledo, Ohio, assignor to The Electric Auto-Lite Company, Toledo, Ohio, a corporation of Ohio

Filed July 8, 1958, Ser. No. 51,697

Term of patent 14 years

(Cl. D26—6)

Fig. I is a perspective front view of an electric storage battery embodying my new design;

Fig. II is a perspective rear view thereof; and

Figs. III and IV are sectional views taken on line III—III and line IV—IV of Figs. I and II respectively.

I claim:

The ornamental design for an electric storage battery, substantially as shown.
